UNITED STATES PATENT OFFICE

127,610

DESIGN FOR A DRAIN SHIELD

Ernest Krumsiek and Ray Kileen, Decatur, Ill.,
assignors to Mueller Co., Decatur, Ill., a corpora-
tion of Illinois

Application July 17, 1940, Serial No. 93,726

Term of patent 7 years

To all whom it may concern:

Be it known that we, Ernest Krumsiek and Ray Kileen, citizens of the United States, residing at Decatur, county of Macon, State of Illinois, have invented a new, original, and ornamental Design for a Drain Shield, of which the following is a specification, reference being had to the accompanying drawing, forming a part thereof.

In the drawing:

Figure 1 is a perspective view of a drain shield showing our new design;

Figure 2 is a rear elevational view; and

Figure 3 is a vertical sectional view looking in the direction of the arrows on line 3-3 of Figure 2.

The characteristic features of our design for a drain shield reside in the specific octagonal con-

figuration and proportions thereof shown in the drawing, comprising a relatively thin sheet formed as shown inclining with a bulge on the face thereof, said inclination, in section, comprising straight lines from the outer edges to the peak at the center opening thereof; the outer, or peripheral configuration being composed alternately of straight line cut-offs and in-turned flanges, all of equal lengths at the peripheral edge, and said inturned flanges having their vertical sides converging inwardly from the peripheral edge of the body portion of the shield.

We claim:

The ornamental design for a drain shield, substantially as shown and described.

ERNEST KRUMSIEK,
RAY KILEEN.
